DESIGN FOR A CASING FOR FURNACES OR THE LIKE

George D. Hauser, Utica, N. Y., assignor to Utica Products Incorporated, Utica, N. Y., a corporation of New York

Application April 28, 1937, Serial No. 69,019

Term of patent 7 years

To all whom it may concern:

Be it known that I, George D. Hauser, a citizen of the United States and a resident of Utica, county of Oneida, State of New York, have invented a new, original, and ornamental Design for Casings for Furnaces or the like, of which the following is a specification, reference being had to the accompanying drawing, forming part thereof, and in which,

Fig. 1 is a front elevational view of a casing for furnaces or the like showing my new design;
Fig. 2 is a side view; and
Fig. 3 is a top view of same.

I claim:

The ornamental design for a casing for furnaces or the like, as shown.

GEORGE D. HAUSER.
